[57] CLAIM

The ornamental design for a scrubbing device, as shown and described.

DESCRIPTION

FIG. 1 is an exploded perspective view of a scrubbing device showing our new design;

FIG. 2 is an enlarged side elevational view, the opposite side being a mirror image thereof;

FIG. 3 is a top plan view thereof;

FIG. 4 is a bottom plan view thereof; and

FIG. 5 is a bottom plan view thereof, shown with the scrubbing head reversed.

The handle is shown broken away in FIGS. 1-5 to indicate indeterminate length.

FIG. 4

FIG. 3

FIG. 5
